UNITED STATES PATENT OFFICE

SAMUEL F. COX, OF DETROIT, MICHIGAN, ASSIGNOR TO DIAMOND POWER SPECIALTY CORPORATION, OF DETROIT, MICHIGAN, A CORPORATION OF MICHIGAN

AIR-HEATER CLEANER

Application filed June 21, 1926. Serial No. 117,548.

The invention relates to cleaners and refers more particularly to an improved cleaning or soot blowing apparatus adapted for regenerative heating devices.

One of the objects of the invention resides in the provision of means for automatically periodically controlling one or more cleaners, whereby cleaning fluid will be discharged adjacent parts of the heating device 10 to be cleaned. A further feature of the invention resides in the provision of control means for the cleaners, insuring discharge of the cleaning fluid in timed relation with the flow of the fluid being heated, generally 15 air, and the flow of the hot gases; preferably so that the cleaning fluid will be discharged only when the hot gases are flowing and in the direction of flow of the hot gases.

Referring to the accompanying drawings 20 in which like reference characters indicate corresponding parts,

Figure 1 is a side elevation view of the heating device showing my invention applied thereto;

25 Figure 2 is a plan view thereof;

Figure 3 is a section through 3—3 of Figure 1, illustrating diagrammatically the control for the blowers for securing the timed relation of the cleaning fluid discharge, with respect to the flow of the hot 30 gases;

Figure 4 is a wiring diagram of the automatic control for the blowers, and

Figure 5 is a detail elevation view along 35 5—5 of Figure 3.

In the drawings, reference character A represents the heater which may be of any preferred construction suitable for use in connection with my invention as will be apparent as the description progresses. The heater A may be formed with three chambers 10, 11 and 12, in each of which is an air valve assembly B, and a valve assembly C for controlling the hot gases, which latter may be termed for convenience a gas valve assembly. The air valve assemblies B, each comprise an inlet valve E communicating with a common air supply chamber 13 and an air outlet valve F communicating with a common outlet chamber 14,

which may lead to any suitable point of use for the heated air, such as a furnace, boiler etc. The valves E and F are mounted for simultaneous actuation on a common valve stem G. Likewise the gas valve assemblies 55 C each comprise inlet valve H, communicating with a common supply chamber 15 for the hot gases and a gas outlet valve J communicating with a common outlet chamber 16 which may lead to a stack in accordance 60 with common practice. The hot gases supplied to chamber 15 may be conducted from any suitable source of supply, such as the product of combustion of a boiler furnace etc. Valves H and J are likewise mounted 65 on a common valve stem K.

A fan 17 furnishes air to be heated, under pressure, to the chamber 13 and an exhauster 18 serves to pull the hot gases through the heating device, the fan and exhauster being 70 operated by a motor 19.

The chambers 10, 11 and 12 may be filled with regenerative material 20, such as thin sheet steel having the property of readily absorbing the heat from the hot flue gases and giving up the absorbed heat to the air as the sheets are alternately subjected to the flow of the hot flue gases and the air to be heated.

Any suitable mechanism may be provided 80 for actuating the air and the gas valve assemblies, the mechanism illustrated being of the type illustrated in the patent to Dryssen, 1,543,909, June 30, 1925. In this 85 type of mechanism, a motor 21 serves to rotate an actuating rod 22 having cranks 23 for rocking means 24, apposite ends of the latter being connected to reciprocate pairs of air and gas valve assemblies B and C respectively, as will be readily understood. It will be seen that the gas and air valves for the same chamber are never opened at the same time, and by suitably arranging the cranks 23, preferably 120° apart, the movement of the valves in the three chambers are such that, at any one moment there are openings corresponding to one full valve opening either for waste gas or for air, all the heating surface of the heater being always in use 95 100

providing continuous flow of air and hot gases through the heater.

In this manner the air from the blower 17 supplies air to be heated, under pressure, to chamber 13 whence it is admitted at proper intervals, controlled by valve E to chambers 10, 11 and 12. In passing through these chambers, the air is heated by the regenerative sheets 20 which have been previously heated by contact with the flow of the hot gases through the chambers, the flow of hot gases being controlled by valves J and H, as will be readily understood.

I have invented simple and efficient means for automatically periodically cleaning the regenerative sheets 20 and other parts of the heater A. If desired, a separate blowing system may be provided for each chamber, each preferably comprising a pair of blower elements L and M having longitudinally spaced cleaning fluid discharge nozzles 25. The blower elements are shown located in the lower portions of the chambers 10, 11 and 12 with nozzles 25 directed upwardly for discharging the cleaning fluid such as steam, air or the like, adjacent the sheets 20 and other parts of the heater to be cleaned. These blower elements may be rockingly or rotatably mounted in rear bearings N and forward wall box bearings O, whence they pass outwardly to the head P. The pairs of blower elements may be supplied with cleaning fluid by branch supply pipes Q, communicating with the main supply header R. Solenoid valves S, S' and S² serve to control the supply of cleaning fluid through the branch supply pipes Q to the respective pairs of blower elements L and M.

For oscillating or rotating the blower element to cause the nozzles 25 to sweep through a suitable arc such as, substantially 90°, each blower element is provided with an actuating lever 26 fixed at one end to the blower element respectively, and having their other ends connected to the reciprocating shaft 27. A motor 28 rotates crank disc 29 through reduction gearing 29', the shaft 27 being reciprocated by connection to the crank disc 29 through crank arm 30. By suitable arrangement of the reduction gearing 29', the element may be rotated at any desired angular velocity. I have found that a speed of two revolutions per minute of the crank disc 29 is suitable under ordinary conditions of operation of the heater A.

In order to automatically periodically actuate the solenoid valves S, S' and S² to supply cleaning fluid to the blower elements at desired intervals, preferably dependent upon the operation of the heater, I have provided an electric contact device T comprising a stationary disc 31 having electric contacts 32, 33 and 34 respectively electrically connected through leads 35, 36 and 37 to the solenoid valves S, S' and S², each of these

contacts also being electrically connected to actuate motor 28. The electric circuit through leads 35, 36 and 37 is established by the common lead 38 terminating at the contact 39 of contact disc 40 rotated for convenience by shaft 22 through suitable reduction gearing 41.

In order to insure operation of the blowers only when the gas valves H and J in the respective chambers are opened, I have provided a rod U fixed to each valve H, which valve controls the flow of waste gases. This rod U passes outwardly through the heater casing through a suitable gland V and carries at its upper extremity a spring W to which is attached electrical contact point X. When the valve is in its open position, contact X engages contact Y serving to complete the respective circuits to the solenoid valves S, S' and S². It is thus obvious that a given solenoid valve can not operate unless the corresponding contacts X and Y are in registration. Contact points 32, 33, 34 and 39 may be readily made sufficiently wide so that operation of the respective solenoid valves is insured. Also reduction gearing 41 may be regulated to produce any desired period of blowing for the blower element suitable for the conditions of operation of the heater. For example the contact disc 40 may be rotated at a speed of one revolution every eight hours to secure a convenient blowing period.

When the motor 28 is actuated all of the blower elements are rotated although cleaning fluid is being supplied to only those elements associated with a single chamber of the heater. So little power is consumed in this actuation of the element that it is more practical to use a single motor as illustrated, than to provide a separate motor for each pair. Obviously, however, the latter is readily possible and would require only obvious slight changes in the wiring system.

It will be apparent that I have thus provided means for automatically periodically cleaning the heating device at desired intervals with respect to the operation of the heater, and more particularly with respect to the operation of the valves controlling the passage of the air and gas through the heater; further I have provided means for imparting rotation to the blower elements during the period of their discharge of the cleaning fluid; further that the blower elements are arranged to blow only when the hot gases are flowing and in the direction of flow of the hot gases. This latter feature of my invention is of particular significance, since the disturbance caused by blowing directly against the incoming air would give rise to serious disadvantage resulting in undesirably contaminating the air with particles of soot and dirt from the heating plates and in clogging air lines and burner or other devices to which the

preheated air is supplied. I have further provided means for automatically controlling the supply of cleaning fluid to the blowers, so as to insure the blowing only when the 5 gas valves are opened, with resulting efficient operation.

What I claim as my invention is:

1. The combination with an air heater having a chamber containing regenerative material, of means subjecting said material alternately to the flow of a heating gas and a fluid to be heated, a blower adapted to discharge cleaning fluid toward said regenerative material, and means operable to positively prevent the supply of cleaning fluid to said blower except when the heating gas is flowing in said chamber.

2. The combination with an air heater having a chamber containing regenerative material of means subjecting said material alternately to the flow of a heating gas and a fluid to be heated, a blower adapted to discharge cleaning fluid toward said regenerative material, means for automatically supplying cleaning fluid to said blower at predetermined intervals, and means operable to positively restrict said supply of cleaning fluid to periods when the heating gas is flowing in said chamber.

3. The combination with an air heater having a chamber containing regenerative material of means subjecting said material alternately to the flow of a heating gas and a fluid to be heated, the flow of heating gas and fluid to be heated being in opposite directions, a blower adapted to discharge cleaning fluid toward said regenerative material, and means operable in dependence upon the operation of said first means to cut off the supply of 40 cleaning fluid to said blower except when the heating gas is flowing in said chamber.

4. The combination with an air heater having a chamber containing regenerative material of means subjecting said material alternately to the flow of a heating gas and a fluid to be heated, a blower adapted to discharge cleaning fluid toward said regenerative material, means for supplying cleaning fluid to said blower, and means restricting said supply to 50 periods when the heating gas is flowing in said chamber, the direction of discharge of the cleaning fluid from the blower being substantially the same as the direction of flow of the heating gas.

5. The combination with an air heater having a chamber containing regenerative material, of valve controlled means for alternately subjecting said regenerative material to a heating gas and a fluid to be heated, 60 means for actuating said valve controlled means, a blower for discharging cleaning fluid toward said regenerative material, and means actuated by the second said means for automatically periodically supplying cleaning fluid to said blower.

6. The combination with an air heater having a chamber containing regenerative material, of valves for alternately subjecting said regenerative material to the flow of a hot gas and a fluid to be heated, means for actuating said valves, a blower for discharging cleaning fluid toward said regenerative material, and means responsive to a predetermined number of said valve actuations for automatically supplying cleaning fluid to said blower.

7. The combination with an air heater having a chamber containing regenerative material, of means subjecting said material alternately to the flow of a heating gas and a fluid to be heated, a rotatable blower provided with a cleaning fluid discharge nozzle directed during rotation of the blower toward parts of the heater to be cleaned including said regenerative material, electrically operated means for supplying cleaning fluid to the blower, electrically operated means for rotating said blower, and means dependent upon the operation of the first mentioned means for automatically periodically energizing the 80 said electrically operated cleaning fluid supply means and rotating means.

8. The combination with a regenerative heating device in which the fluid to be heated and the fluid giving off heat pass alternately through a plurality of chambers containing regenerative material, of a blower device for each of said chambers, electrically operated means controlling the supply of cleaning fluid to the respective blowers, and means for selectively, periodically and automatically energizing the said electrically operated means, said last mentioned means being operable to prevent the discharge of cleaning fluid to each chamber when the fluid to be heated is passing through the respective chamber.

9. The combination with a regenerative heating device in which the fluid to be heated and the fluid giving off heat pass alternately through a plurality of chambers containing regenerative material, of a blower device for each of said chambers, electrically operated means controlling the supply of cleaning fluid to the respective blowers, electrically operated means for rotating said blowers, means dependent upon the flow of fluid giving off heat through the said chamber or selectively, automatically, and periodically energizing the said cleaning fluid controlling means, and means actuatable by the last said means for energizing the said blower rotating means whenever cleaning fluid is being delivered to the corresponding blower.

10. The combination with a regenerative heating device including a chamber containing regenerative material, separate and simultaneously actuatable heating gas inlet and outlet valves controlling the passage of heating gas to and from said chamber respec-

tively, separate and simultaneously actuatable inlet and outlet valves controlling the flow of the fluid to be heated to and from said chamber and means for alternately unseating said groups of valves, of a blower device for cleaning said regenerative material, and means operable in timed relation to said last mentioned means for automatically periodically supplying cleaning fluid to said blower.

11. The combination with a regenerative heating device including a chamber containing regenerative material, separate and simultaneously actuatable heating gas inlet and outlet valves controlling the passage of heating gas to and from said chamber respectively, separate and simultaneously actuatable inlet and outlet valves controlling the flow of the fluid to be heated to and from said chamber and means for alternately unseating said groups of valves, of a blower device for cleaning said regenerative material, means for automatically periodically supplying cleaning fluid to said blower, and means controlled by one of said groups of valves for restricting the supply of cleaning fluid to periods when the said heating gas valves are unseated.

12. The combination with an air heater having a chamber containing regenerative material, of means subjecting said material alternately to the flow of a heating gas and a fluid to be heated, a blower adapted to discharge cleaning fluid toward said regenerative material and means dependent upon the operation of said first mentioned means for limiting the supply of cleaning fluid to said blower to periods when the heated gas is flowing in said chamber.

13. The combination with an air heater having a chamber containing regenerative material, of a valve for controlling the passage of a heating gas through the said chamber, a blower for discharging cleaning fluid toward said regenerative material and means operable upon a predetermined movement of the said valve for cutting off the supply of cleaning fluid to the said blower.

14. The combination with an air heater having a chamber containing regenerative material and a passage for supplying a heating gas to said chamber, of a member movable to open and close said passage, a blower for discharging cleaning fluid toward said regenerative material, a valve controlling the supply of cleaning fluid to said blower, and means operable in dependence upon the movement of said member for controlling the actuation of said valve.

15. The combination with an air heater having a chamber containing regenerative material and a passage for supplying a heating gas to said chamber, of a member movable to open and close said passage, a blower for discharging cleaning fluid toward said regenerative material, a valve controlling the

flow of cleaning fluid to said blower, means for actuating said valve, and means operable upon movement of said member to close said passageway for effecting a closing of said valve by said valve actuating means.

In testimony whereof I affix my signature.

SAMUEL F. COX.
